CLAIM

The ornamental design for a bilge pump mounting bracket, as shown and described.

DESCRIPTION

FIG. 1 is a bottom plan view of a bilge pump mounting bracket embodying my new design;

FIG. 2 is a top plan view of the bilge pump mounting bracket;

FIG. 3 is a side elevational view of the bilge pump mounting bracket;

FIG. 4 is a side elevational view of the opposite side of the bilge pump mounting bracket;

FIG. 5 is a rear elevational view of the bilge pump mounting bracket; and,

FIG. 6 is a front elevational view of the bilge pump mounting bracket.
